GASEOUS FUEL BURNER

Robert H. Solem, Rockford, Ill., assignor to
 Eclipse Fuel Engineering Co., Rockford, Ill., a
 corporation of Illinois

Application June 27, 1945, Serial No. 601,745

3 Claims. (Cl. 158—99)

1

The present invention relates generally to gaseous fuel burners. More particularly the invention relates to that type of burner which comprises a water jacketed tube, means for supplying a mixture of gaseous fuel under pressure to one end of the tube, and means for circulating water through the jacket for tube cooling purposes.

The primary object of the invention is to provide a burner of this type having novel means for automatically preventing the supply of gaseous fuel under pressure to the tube in the event there is a failure of the supply of water to the water jacket around the tube.

Other objects of the invention and the various advantages and characteristics of the present gaseous fuel burner will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a side view showing a gaseous fuel burner embodying the invention in operative relation with a Bessemer converter;

Figure 2 is a longitudinal section of the burner;

Figures 3 and 4 are transverse sections taken, respectively, on the lines 3—3 and 4—4 of Figure 2; and

Figure 5 is an enlarged sectional view of the pressure switch constituting part of the means for automatically preventing the supply of gaseous fuel under pressure to the tube in the event there is a failure of a supply of water to the water jacket around the tube.

The gaseous fuel burner which is shown in the drawings constitutes the preferred form or embodiment of the invention. It is designed primarily as a preheating medium or instrumentality for a Bessemer converter C and comprises an elongated tube 5. The converter C is of standard or conventional design and embodies a metallic receptacle c having a refractory lining c¹. The receptacle has a mouth at the upper end thereof and is adapted to receive a charge of molten iron, as well understood in the art. It is illustrated as being of the bottom-blow type and embodies a pair of outwardly extending diametrically opposite trunnions c² which are journaled in a pair of bearings c³ at the upper ends of a pair of standards c⁴ and permit the receptacle to be tilted in a vertical plane.

2

The tube 5 is adapted in connection with use of the burner to extend downwards through the mouth of the converter receptacle c into the receptacle interior, as shown in Figure 1. It is of such length that when it is in its operative position the lower end thereof terminates adjacent the bottom of the receptacle. The lower or discharge end of the tube is provided with a nozzle 6. The upper or receiving end of the tube is connected by a conduit 7 to receive a mixture of gas and air under pressure from a compressor 8. The latter is illustrated in Figure 1 of the drawing as being of the centrifugal type and constitutes a source for supplying a mixture of gas and air under pressure to the tube 5 for discharge via the nozzle 6. It is mounted on a fixed platform 9 adjacent the Bessemer converter C and consists of a volute casing 10 and a rotor (not shown). The casing has a central inlet 11 at one side thereof and embodies a tangential outlet 12. The rotor of the compressor is driven by an electric motor 13 and this is located adjacent the other side of the compressor casing and is suitably mounted on the platform 9. The armature shaft 25 of the motor extends through said other side of the compressor casing and is connected to the hub of the rotor. The inlet of the casing of the compressor is connected by a pipe 14 to an apparatus 15 for proportionally mixing gas and air. 30 Such apparatus is preferably of the type which is shown in, and forms the subject matter of, United States Letters Patent No. 2,963,453, granted to Garret W. McKee on December 8, 1936. It comprises a vertically extending cylindrical housing 35 16 having a gas and air mixing chamber 17 in the central portion thereof. The pipe 14 communicates with this chamber. Air under atmospheric pressure is admitted into the mixing chamber by way of a valve controlled orifice in a plate 18 at the bottom of the housing. Gas is introduced into the mixing chamber by way of a pipe 19. Such pipe is connected to receive manufactured or natural gas under pressure from any suitable source and includes a zero governor 20 for reducing the gas to atmospheric pressure prior to entry into the mixing chamber 17. When the compressor 8 is in operation it draws a mixture of gas and air from the mixing chamber 17 in the apparatus 15 and supplies the mixture under pressure to the tube 5 via the conduit 7. The latter comprises a pipe 21 which is connected to, and leads from, the outlet 12 of the compressor casing 10, a pipe fitting 22 at the upper or receiving end of the burner tube 5, and a flexible hose 23. The hose, as shown in Figure 1, extends be-

tween, and is connected to, the pipe 21 and the pipe fitting 22. By reason of its flexibility the hose permits movement of the tube 5 in connection with shift of the burner into and out of its operative position with respect to the Bessemer converter C. The mixture which is supplied by the compressor 8 to the tube is essentially a combustible one, although it is preferably over rich in gas. The nozzle 6 at the lower or discharge end of the tube 5 serves to discharge the mixture for purposes of combustion. It comprises a sleeve 24 which is axially aligned with the tube 5 and has the upper end thereof connected to the lower or discharge end of the tube 5 by a screw thread connection 25. A downwardly tapered or frusto-conical wall 26 is disposed in the central portion of the interior of the sleeve 24 of the nozzle 6. This wall serves to increase the velocity of the gas and air mixture and has holes 27 therein for permitting a portion of the mixture to flow outwards into the space between the wall 26 in the lower end of the sleeve. The portion of the mixture which flows outwards through the holes 27 expands in said space and serves as ignition means for the portion of the mixture that passes axially through the downwardly tapered wall 26.

In addition to the nozzle equipped tube 5 the burner comprises a water jacket 28, means for circulating water through the jacket and means for supplying secondary air to the mixture of gas and air under pressure emanating from the nozzle 6.

The water jacket 28 surrounds the tube and comprises a cylindrical side wall 29, a lower end wall 30, and an upper end wall 31. The cylindrical side wall 29 of the jacket is of materially greater diameter than the tube 5 and is positioned concentrically with respect to the latter. It is substantially the same in length as the tube and defines with the latter an annular space 32. The lower end wall 30 of the jacket serves as a closure for the lower end of the space 32 and extends across, and is welded to, the lower end of the cylindrical side wall 29. The central portion of the lower end wall 30 abuts against, and is welded to, the lower end of the sleeve 24 of the nozzle 6 and embodies a circular hole 33. The latter is in registry with the sleeve interior and permits discharge of the mixture of gas and air under pressure from the nozzle. The upper end wall 31 of the water jacket 28 serves as a closure for the upper end of the annular space 32. It extends across, and is welded to, the upper end of the cylindrical side wall 29 and is disposed a small distance beneath the pipe fitting 22 of the conduit 7. The central portion of the upper end wall 31 has a central hole 34 through which the upper or receiving end of the tube 5 extends. The hole defining portion of the upper end wall 31 is welded to the adjacent portion of the tube 5 in order to prevent leakage of water from the space through the hole 34.

The means for circulating water through the water jacket 28 comprises an annular manifold 35, a plurality of supply pipes 36, and a discharge pipe 37. The manifold 35 extends around the upper end of the side wall 29 of the water jacket 28 and is connected by way of a conduit 38 to receive water under pressure from a source (not shown). The conduit 38 comprises a pipe 39 leading from the source of water under pressure and disposed beneath the platform 9, an inlet pipe 40 leading to, and communicating with, the manifold 35, and a flexible hose 41 between

the pipe 39 and the inlet pipe 40. The hose 41 permits movement of the manifold 35 in connection with shift of the burner into and out of its operative position with respect to the converter C. The pipes 36 are disposed in, and extend lengthwise of, the annular space 32 in the water jacket 28. They are disposed in an annular series around the tube 5, as shown in Figure 3. The lower ends of the pipes 36 are closed. The upper ends of the supply pipes are bent outwards at right angles, extend through holes 42 in the upper end of the cylindrical side wall 29, and are connected to, and communicate with the interior of, the annular manifold 35. Each of the supply pipes 36 is provided on the outer side portion thereof with a longitudinal series of discharge holes 43. These holes face in the direction of the inner periphery or surface of the cylindrical side wall 29 of the water jacket 28 and serve to jet streams of water against said inner periphery of the water jacket side wall 29. The streams of water emanating from the discharge holes 43 serve to wipe away the steam which forms on the inner periphery of the side wall 29 during operation of the burner and thus prevent lime or other substances from accumulating on said inner periphery of the water jacket side wall and clogging the jacket as a whole. The discharge pipe 37 is connected to, and extends radially from, the upper end of the cylindrical side wall 29 of the water jacket 28. It communicates with the upper portion of the space 32 and is connected to a drain pipe 44 by way of a flexible hose 45. The drain pipe 44, as shown in Figure 1, is disposed under the platform 9. The hose 45 coacts with the hoses 23 and 41 to permit movement or shift of the burner. When the burner is in operation and water under pressure is supplied to the pipe 39 the water travels through the hose 38 and then into the annular manifold 35 via the inlet pipe 40. From the manifold the water under pressure flows into and through the supply pipes 36 and is then jetted in stream form outwards towards the inner periphery or surface of the side wall 29 of the water jacket. After impinging against the inner periphery of the water jacket side wall the water flows upwards through the space 32 and then is discharged from the water jacket via the discharge pipe 37, the hose 45, and the drain pipe 44. The water that circulates through the space 32 serves to prevent overheating of the tube 5 and the nozzle 6 while the burner is in operation.

The means for supplying secondary air to the gas and air mixture emanating from the nozzle 6 embodies a ring shaped header 46 and a plurality of pipes 47. The header is disposed directly above the upper end wall 31 of the water jacket 28 and surrounds the upper or receiving end of the tube 5. It is connected to a source of air under pressure by way of a pipe fitting 48, an inlet pipe 49 and a flexible hose 50. The pipe fitting 48 is connected to, and leads from, the source of air under pressure and is disposed beneath the platform 9. The inlet pipe 49 is connected to, and communicates with, the header 46, as shown in Figures 2 and 4. The flexible hose 50 extends between, and is connected to, the pipe fitting 48 and the inlet pipe 49 and serves with the other flexible hoses to permit movement or shift of the burner. The pipes 47 extend longitudinally through the space 32 within the water jacket 28 and are arranged in an annular series around the tube 5. Preferably the pipes 47 and the supply pipes 36 are arranged in alternate rela-

tion. The upper ends of the pipes 47 extend through holes 51 in the upper end wall 31 of the water jacket 28 and are connected to, and communicate with, the header 46. The lower ends of the pipes 47 extend through holes 52 in the lower end wall 30 of the water jacket and terminate adjacent said lower end wall. When the burner is in operation air under pressure flows into the header 46 via the pipe fitting 48, the hose 50 and the inlet pipe 49 and then flows into and through the pipes 47 and is discharged adjacent the central hole 33 in the lower end wall 30 of the water jacket 28. The secondary air emanating from the lower ends of the pipes 47 serves to complete combustion.

A supporting structure 53 serves as a medium for supporting the burner when the latter is in or out of its operative position with respect to the Bessemer converter C. This structure is portable and comprises a caster equipped truck 54, a standard 55 on the truck and an upwardly inclined arm 56 at the upper end of the standard. The outer end of the arm 56 is shaped to form a socket 57. The burner extends through, and is slidably mounted in, this socket. A set screw 58 extends through the socket defining portion of the arm 56 and serves releasably to hold the burner in the various positions into which it is slid or shifted. When the burner is to be used the supporting structure is moved into a position wherein it is disposed adjacent the Bessemer converter C and the arm 56 overlies the mouth of the converter receptacle. The set screw 58 is then loosened and the burner is shifted downwards into its operative position wherein it extends through the mouth of the converter receptacle and the lower end thereof is disposed adjacent the bottom of the receptacle. As soon as the burner is shifted into place the set screw 58 is tightened so as to lock the burner against axial displacement relatively to the socket 37. After the burner has served its purpose as a preheating medium for the converter C the set screw 58 is loosened and the burner is slid upwards until the lower end thereof is disposed in the socket 57. Thereafter the set screw 58 is tightened and the supporting structure 53 is shifted away from the converter to some other location. The flexible hoses 23, 41, 45 and 50 permit shift of the burner as hereinbefore pointed out.

In order automatically to prevent delivery or supply of the mixture of gas and air under pressure to the tube 5 in the event that there is a failure of the supply of water under pressure to the water jacket 28 a pressure switch 59 and a solenoid valve 60 are provided. The switch, as hereinafter described, is in circuit with the electric motor 13 for driving the rotor of the compressor 8. The pressure switch 59 comprises a T fitting 61, a spring compressed bellows 62, and a switch 63. The end branches of the T fitting 61 are included in, and form a part of, the pipe 39 which leads from the source of water under pressure to the flexible hose 38. The bellows 62 is connected to the central branch of the T fitting 61 and is adapted when water under pressure flows through the T fitting, to expand against the force of its spring. When the flow of water under pressure through the fitting 61 stops or the water flowing through the fitting drops to a predetermined pressure the bellows collapses. The switch 63 comprises a fixed contact 64 and a contact 65. The last mentioned contact is mounted on the bellows 62 and is adapted when

the bellows is expanded to move into engagement with the fixed contact 64 and thus effect closing of the switch 63. The solenoid valve 60 is a normally closed valve and is included in the gas supply pipe 19 ahead of the zero governor 20. It comprises a casing 66 having in the interior thereof a partition 67 with a valve seat 68 therein. It also comprises a vertically movable valve member 69 which is urged downwards into seated relation with the seat either by gravity or a spring. The solenoid part of the solenoid valve 60 comprises a coil 70 and a vertically movable armature 71. The valve member 69 is applied to the lower end of the armature. When the solenoid part of the solenoid valve 60 is energized the armature 71 is retracted and shifts the valve member 69 upwards into its open position. When the solenoid part of the valve is deenergized the armature 71 moves downwards and effects closing of the valve member 69. The electric motor 13 and the coil of the solenoid part of the valve 60 are supplied with current from a pair of terminals 72 and 73 under control of the automatic pressure switch 59. The terminals are connected by line conductors to a source of current supply. A conductor 74 leads from the terminal 72 to the fixed contact 64 of the switch 59 and includes a master switch 75. A conductor 76 leads from the movable contact 65 of the pressure switch 59 and includes a branch 76^a leading to one of the terminals of the electric motor 13 and a branch 76^b leading to one end of the coil 70 of the solenoid part of the solenoid valve 60. A conductor 77 is connected to, and extends between, the other terminal of the electric motor and the terminal 73. The other end of the coil 70 is connected to said terminal 73 by way of a conductor 78. Because of the arrangement of the conductors the motor 13 and the coil 70 of the solenoid valve are in parallel. When the switches 63 and 75 are closed the following circuit is established; terminal 72, conductor 74, switch 63, conductor 76, branch 76^a, electric motor 13, conductor 77, branch 76^b, coil 70, conductor 78 and terminal 73. When this circuit is established the motor 13 is set in operation and the solenoid valve 60 is caused to open. As soon as the motor 13 starts and the solenoid valve 60 opens the compressor 8 operates to deliver a mixture of gas and air under pressure to the burner tube 5. In the event of failure of supply of water under pressure to the jacket 28 during operation of the burner the pressure switch 59 opens and automatically breaks the aforementioned circuit. When the circuit is broken the compressor 8 stops and the solenoid valve 60 closes. As the result of the action of the pressure switch 59 there can be no feed or supply of gas and air under pressure to the burner tube in the event of failure of the supply or delivery of water under pressure to the water jacket 28.

When it is desired to use the burner for converter heating purposes the supporting structure 53 is shifted into a position wherein it is disposed adjacent the converter and the arm 56 overhangs the mouth of the receptacle. After this operation the operator arranges for the supply of water under pressure to the pipe 35 and the supply of air under pressure to the pipe fitting 48. Thereafter the switch 75 is closed so as to start the electric motor 13 and cause the compressor 8 to supply a mixture of gas and air under pressure to the burner tube 5. As soon as the compressor is set into operation the burner, while in its up or inoperative position, is ignited. After igniting,

the burner the latter is shifted downwards into the interior of the converter receptacle until the nozzle 6 is disposed adjacent the bottom of the converter receptacle. The burner is allowed to operate until the converter is preheated to the desired extent. During operation of the burner the refractory liner ^{c1} is dried and the products of combustion flow upwards through the mouth of the converter receptacle. In the event that the supply of water under pressure to the water jacket 28 should fail for any reason whatsoever the pressure switch 59 opens automatically, as hereinbefore described, and breaks or interrupts the circuit through the electric motor 13 and the solenoid part of the solenoid valve 60. Immediately upon opening of the pressure switch the compressor 3 stops and the solenoid valve 60 closes and shuts off the supply of gas under pressure to the zero governor 20. After the Bessemer converter C has been preheated to the desired extent the burner is stopped and is then slid upwards out of the converter receptacle.

The herein described gaseous fuel burner effectively and efficiently fulfills its intended purpose and is characterized by simplicity of design and long life. It is readily movable from place to place and is not likely to burn out as a result of cooling which is effected by circulation of water through the jacket 28.

Whereas the burner has been described as being primarily designed for use in preheating a Bessemer converter it is to be understood that it has many other capabilities of use. It is also to be understood that the invention is not to be restricted to the details set forth since these may be modified within the scope of the appended claims without departing from the spirit and scope of the invention.

This application is a division of that filed by me on April 30, 1943, Serial No. 485,095.

Having thus described the invention what I claim as new and desire to secure by Letters Patent is:

1. A heating apparatus comprising in combination a water-jacketed gaseous fuel burner, means for supplying a mixture of gaseous fuel under pressure to said burner, including a compressor and an electric motor for driving the compressor, means for circulating water through the water jacket of the burner, including inlet and outlet connections leading to and from the jacket, respectively, and means for automatically rendering the supply means inoperative upon failure of the circulating means, said automatic means embodying a pressure switch consisting of a pressure responsive part connected to, and responsive to variations in the pressure of the water in, one of the connections and a switch part connected to be actuated by the pressure responsive part and arranged in circuit with the motor.

2. A heating apparatus comprising in combination a water-jacketed gaseous fuel burner, means for supplying a mixture of gaseous fuel under pressure to the burner, including a pipe having a solenoid valve therein, means for circulating water through the water jacket of the burner, including inlet and outlet connections leading to and from said jacket, respectively, and means for automatically rendering the supply means inoperative upon failure of the circulating means, said automatic means embodying a pressure switch consisting of a pressure responsive part connected to, and responsive to variations in the pressure of the water in, one of the connections and a switch part connected to be actuated by the pressure responsive part and arranged in circuit with the solenoid part of the solenoid valve.

3. A heating apparatus comprising in combination a water-jacketed gaseous fuel burner, means for supplying a mixture of gaseous fuel under pressure to said burner, including a compressor, an electric motor for driving the compressor, and a supply pipe leading to the suction side of the compressor and having a solenoid valve therein, means for circulating water through the water jacket of the burner, including inlet and outlet connections leading to and from said jacket, respectively, and means for automatically rendering the supply means inoperative upon failure of the circulating means, said automatic means embodying a pressure switch consisting of a pressure responsive part connected to, and responsive to variations in the pressure of the water in, one of the connections and a switch part connected to be actuated by the pressure responsive part and arranged in circuit with the motor and the solenoid part of the solenoid valve.
